UNITED STATES PATENT OFFICE.

WILLIAM J. ASHLEY, OF DENVER, COLORADO, ASSIGNOR, BY DIRECT AND MESNE ASSIGNMENTS, OF ONE-SIXTH TO EDWIN C. GALBREATH, ONE-SIXTH TO CHARLES F. SEITZ, AND ONE-THIRD TO ROBERT C. ALBROOK, ALL OF DENVER, COLORADO.

ELECTRIC RAILWAY-SIGNAL.

No. 917,703.

Specification of Letters Patent.

Patented April 6, 1909.

Application filed May 11, 1908. Serial No. 432,264.

To all whom it may concern:

Be it known that I, WILLIAM J. ASHLEY, a citizen of the United States, residing in the city and county of Denver and State of Colorado, have invented certain new and useful Improvements in Electric Railway-Signals; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in railway signals, my object being to provide a construction whereby, whenever a rail is misplaced, or a culvert or bridge carried away, or the track so impaired by flood or fire as to wreck a train, a signal will be automatically given by closing an electric light circuit extending along the line of track between stations and provided with lamps or other danger signals, or both, arranged at such intervals that it will be practically impossible for the danger signals to be disregarded, since they will be in plain view not only of the train men, but also of the passengers riding upon the train.

My improved construction also includes means whereby the circuits in which the danger signals are located, may be manually closed when, for any reason this may be desirable, as, for instance, in the event that a train has passed a station contrary to orders and is about to meet another train between the said station and the next, making a wreck practically unavoidable, so far as the ordinary means of notifying the train men is concerned. In that event, the agent at either station having discovered the condition of affairs, may immediately notify both trains by manually closing the circuit in which the danger signals are located, thus displaying these signals the entire length of the track between stations.

Having briefly outlined my improved construction, I will proceed to describe the same in detail, reference being made to the accompanying drawing in which is illustrated an embodiment thereof.

In this drawing, Figure 1 is a view principally diagrammatic, illustrating my improved railway signaling system, the appa-

ratus at and between two stations being indicated. Fig. 2 is a similar view illustrating the apparatus at one station, the danger signals in this case being shown in detail, and the entire apparatus on a larger scale than in Fig. 1. Fig. 3 is a detail view showing a rail of the track, and illustrating the manner of connecting the conductors of the magnet circuits with the rail, the parts being shown on a relatively large scale. Fig. 4 is a similar view, illustrating anchoring means for a conductor of the magnet circuit, whereby, if a rail is displaced, the conductor will be broken. Fig. 5 is a section taken on the line 5—5 of Fig. 4. Fig. 6 is a section taken on the line 6—6 of Fig. 3.

The same reference characters indicate the same parts in all the views.

Let the numeral 5 designate each of two stations provided with a double switch board 6, upon which are mounted two electro magnets 7, provided with armatures 8, which are held in the raised position, or that shown in Fig. 1, and at the right in Fig. 2, when the magnet circuit is closed. Each magnet circuit may be traced as follows: A conductor 9 leads from one terminal of the magnet to one pole 10 of an electric source 12. From the opposite pole 13 of this source a conductor 14, leads downwardly to the track and extends along the track to a position half way, or approximately half way, between the two stations, where it forms a loop and extends back from the extremity of the loop, from which point the conductor is designated 15, to the opposite terminal of the magnet. Hence, this magnet circuit is normally closed.

The conductors 14 and 15 should be connected with the track rails in such a manner that if a rail is displaced, disturbed or broken, in such a way as to make it dangerous for a train to pass, one or both of these conductors will be broken, thus breaking the magnet circuit and allowing the armature 8 to drop, the latter being so arranged as to produce this result. This armature is hinged at 16, and when the magnet is energized, is held in the upright position by virtue of the magnetic force. However, when the magnet is deenergized, the armature will fall downwardly, and a contact 17 with which it is provided, engages two contacts 18 and 19, bridging the same, and closing an electric

light circuit which is supplied with current from a generator 20.

The electric light circuit receives its supply from feed wires A and B, connected with the 5 opposite poles 21 and 22 of the generator 20. The electric light circuit may be traced as follows, referring more particularly to Fig. 1 of the drawing: From the feed wire A, a conductor 23 leads to a conductor 24, which 10 is connected with a contact 25, from which leads a conductor 26, to an overhead wire 27, mounted on posts 28. The opposite extremity of this wire 27 leads to a contact 28 of the switch board 5 of another station. 15 From the contact 28 leads a conductor 29, from which a conductor 30 leads to the feed wire B, which is connected with the brush 22 of the generator 20, the opposite brush 21 being connected with the feed wire A, as 20 heretofore explained. From the feed wire A, a conductor 43 leads to a conductor 42 which is connected with a contact 41, from which a conductor 40 leads to a contact 19. From the opposite contact 18, a conductor 39 25 leads to a conductor 38 which merges into an overhead conductor 37 supported by the posts 28. From the conductor 37 a conductor 35 leads downwardly and from this last named conductor, a conductor 84 leads 30 to the contact 19 of the switch board of the station farther to the left (see Fig. 1). From the opposite contact 18 of this switch board, a conductor 34 leads to a contact 33. From the contact 33 leads a conductor 32 from 35 which conductor, a conductor 31 leads to the feed wire B.

As heretofore explained, each switch board is double, containing two sets of mechanism, each of which is connected with a corresponding set of mechanism mounted on the double switch board of an adjacent station. Any desired number of incandescent lamps are connected in multiple arc with the overhead wires 27 and 37. These lamps are 45 designated 50. A conductor 51 leads from the overhead conductor 37 to each lamp, and a conductor 52 from the overhead wire 27 to each lamp. An incandescent lamp 36 is also mounted on each half of the switch 50 board, these lamps being connected in multiple arc with the overhead wires 27 and 37 by branch conductors 53 and 54.

Assuming now that the magnet 7 mounted on the right half of the switch board farther 55 to the left in Fig. 1, is deenergized by the breaking of the magnet circuit through the displacing of a rail or other accident, the current may be said to pass from the feed wire A through the conductor 23, the conductor 24, the contact 25, the conductor 26, and thence through the various clamps connected with the light circuit, and thence through the overhead wire 37, the conductor 35, the conductor 84 to a contact 19, and 60 thence through the contact 17 of the arma-

ture 8 of a magnet 7 to a contact 18, and thence through the conductor 34 to the contact 33, the conductor 32, thence through the conductor 31, to the feed wire B, completing the circuit. In this case it will, of course, be understood that when the magnet 7 just referred to, is deenergized, the armature 8 will drop, bringing its contact 17 into engagement with the contacts 18 and 19, thus bridging the space between the two contacts, whereby the circuit is completed. Now, if we assume that the magnet circuit in which the magnet 7 is located, mounted upon the left half of the switch board farther to the right in Fig. 1, is broken by the displacement 75 of a rail, or other cause, the magnet will be deenergized and the armature 8 will drop, bringing its contact 17 into engagement with the contacts 18 and 19, thus closing the electric light circuit, in which event the path of 80 the current may be said to be as follows: From the feed wire A through the conductor 43, the conductor 42, the contact 41, the conductor 40, the contact 19, the contact 17 of the armature 8, the contact 18, the conductor 39, the conductor 38 and thence through the overhead feed wire 37. In this case the current passes from the overhead wire 37 through the various lamps of the electric circuit, to the feed wire 27, and 85 thence back through the contact 28, the conductor 29, and the conductor 30, to the feed wire B, thus completing the circuit.

Attention is called to the fact that the mechanism on each half of each of the switch 100 boards 5 at each station, is provided with a hand-operated switch 55. This switch on the left half of the right hand switch board (see Fig. 1), has its arms pivotally connected with the contacts 28 and 41, and when the switch is closed, its arms will engage the contacts 56 and 57, the latter of which is connected with the conductor 27 by a conductor 58, while the conductor 38 is connected with the contact 56, the conductor 105 38 merging into the overhead conductor 37, as heretofore explained. The hand switch 55 on the right half of the switch board 5, farther to the left in Fig. 1, has its arms pivotally connected with the contacts 25 and 33, 110 and when the switch is closed, its arms engage contacts 59 and 60. From the contact 59 a branch conductor 61 leads to the conductor 26; while, from the contact 60 leads a conductor 62, which merges into the overhead conductor 37. From the foregoing it 115 will be understood, that if either of these hand switches is closed, or caused to engage the contacts 56 and 57 in one case, or the contacts 60 and 61 in the other case, the electric light circuit connecting the two stations, will be closed and all the lamps lighted. This hand switch will be found particularly 120 advantageous in the event that a train passes a station without orders, and under such 125 130

circumstances that it will collide with another train, in the event that no danger signal is given. The station agent may then close the electric light circuit between the 5 stations by simply throwing the hand switch to the closing position, which is illustrated at the left side of the switch board 5 in Fig. 2.

In addition to the lamp signals, other danger signals 63 (see Fig. 2) may be displayed. These signals are more especially intended for use as day signals. Each signal 63 is connected with a bell crank lever 64, fulcrumed at 65. The short arm 66 of this lever is connected by means of a link 67, 10 with a core or reciprocating part 68 of a solenoid magnet 69. In this event, the conductor 51 leading from the overhead wire 37, 15 may be said to pass to one terminal of the magnet 69, the other terminal of the magnet 20 being connected with a conductor 70, leading to the lamp, which is also connected by means of the conductor 52 to the overhead feed wire 27. It will thus be seen that whenever the lamp circuit is closed, all of the 25 solenoid magnets 69 upon the line will be energized, and the core 68 of each magnet drawn inwardly, thereby displaying the red signal 63 by throwing the signals out of the box, or casing 71, in which they are normally 30 inclosed. There may be a signal 63 for each lamp 50 between the two stations.

The manner of connecting the wires of the magnet circuit with the track rails, is illustrated in Figs. 3 to 6. In these figures the 35 conductor may be designated 15, and is connected with the rail by a metal plate 72, the said plate having its upper extremity wrapped around the wire, as shown at 73, from which point the plate passes down- 40 wardly, first in contact with the web of the rail, thence outwardly and downwardly underneath the base of the rail, its opposite extremity being turned upwardly into contact with the upper surface of the rail base. 45 In this way the wire is securely connected with the rail, and if the rail is displaced or broken, the wire will be broken.

As shown in Figs. 4 and 5 of the drawing, an anchor 74 is connected by means of a 50 cable 75, with the conductor 15, the plate 72 being cut away, as shown at 76 (see Fig. 4), for the purpose. As this anchor is embedded in the earth, if the rail is displaced, its movement will break the wire, since the resistance 55 offered by the anchor will be sufficient for this purpose.

In Figs. 3 and 6, the wire 15 is connected with the rail by forming a recess 77 in a fish plate 78, whereby the conductor is clamped 60 between the fish plate and the rail. In this case, if the rail is broken, or moved sufficiently to produce an accident, the conductor will also be broken. It is evident that various other means may be resorted to 65 for connecting the conductors of the magnet

circuits with the rails, whereby as the rails are injured or misplaced, these wires or conductors will be broken, and the magnet with which they are connected, deenergized, resulting in the closing of the magnet circuit 70 by the dropping of the armature 8, whereby its contact 17 is caused to bridge the space between the contacts 18 and 19, thus closing the signal circuit.

It is evident that where tunnels and snow 75 sheds are located, the conductors or wires of the magnet circuit may be carried overhead, so that, in the event the tunnel or snow shed caves in, or is sufficiently injured to cause an accident, the wires will be broken and the 80 magnet or magnets deenergized, resulting in the closing of the signaling circuit, as heretofore explained.

Having thus described my invention, what I claim is:

1. In electrical signaling apparatus for railways, the combination of a normally open electric light circuit arranged along the track in suitable proximity thereto, and a normally closed magnet circuit whose wires 90 are arranged along the roadbed in such a manner that the circuit will be broken by the disturbance of the track, the magnet being provided with an armature normally held in the raised position by the magnetic force, 95 the electric light circuit having contacts so arranged with reference to the armature, that, as the magnet is deenergized and the armature falls, it will engage the said contacts and close the electric light circuit, substantially as described.

2. In electrical signaling railway apparatus, the combination of an electrical circuit arranged along the line of the railway in suitable proximity thereto, signaling devices 105 arranged in the said circuit, the said circuit being normally open, and electro-magnetic means for closing the signaling circuit, a circuit in which said means is located, the magnet circuit being provided with conductors extending along the roadbed in such proximity to the track, that the disturbance of the track or roadbed will break the circuit, the electro-magnetic means being provided with an armature normally held in the 115 raised position by the magnetic force, and arranged to fall when the circuit is broken and the magnet deenergized, and the signaling circuit having separated contacts arranged to be bridged by the armature of the electro-magnetic means, substantially as described.

3. In electrical signaling apparatus, the combination of a normally open signaling circuit arranged along the line of railway and in suitable proximity to the track 125 thereof, stations connected by the said circuit, a magnet circuit at each station, the said circuit having conductors extending along the roadbed in such proximity to the track, that the disturbance of the track will 130

break the magnet circuit, each magnet having an armature normally held in the raised position by the magnetic force, the said armature, however, being arranged to fall when the magnet is deenergized by the breaking of the magnet circuit, the signaling circuit having a pair of separated contacts at each station, the said contacts being so arranged that, as the armature of the magnet falls, it will bridge the contacts and close the signaling circuit, substantially as described.

4. In electrical signaling apparatus, the combination with stations arranged along 15 the line of railway, normally open signaling circuits connecting the said stations, a magnet circuit connected with each station and having conductors extending along the line of track and in such proximity thereto that 20 the disturbance of the track will break the magnet circuit, the magnet circuit of each station being distinct from the circuit of the other station, each magnet having an armature normally held in a predetermined 25 position when the magnet circuit is closed, the said armature being arranged to move when the magnet circuit is broken, the signaling circuit being provided at each station with a pair of separated contacts adapted to

be bridged by the moving of the armature 30 incident to the breaking of the magnet circuit, whereby the signaling circuit is automatically closed, substantially as described.

5. In electrical signaling apparatus for railways, the combination of a normally 35 open signaling circuit arranged along the line of railway, and electro-magnetic means for closing the signaling circuit, a circuit in which the electro-magnetic means is located, the last named circuit having conductors 40 extending along the roadbed and arranged in such proximity to the track that the disturbance of the latter will break the magnet circuit, the electro-magnetic means having a part, normally held in the raised position 45 by the magnetic force, and adapted to fall when the magnet circuit is broken, the two contacts adapted to be engaged by the movable part to close the signaling circuit when the circuit of the electro-magnetic means is 50 broken, substantially as described.

In testimony whereof I affix my signature in presence of two witnesses.

WILLIAM J. ASHLEY.
